UNITED STATES PATENT OFFICE.

WILLIAM R. PENSCHUCK, OF ST. PAUL, MINNESOTA.

ENGINE.

1,191,343.

Specification of Letters Patent. Patented July 18, 1916.

Application filed August 1, 1914. Serial No. 854,461.

To all whom it may concern:

Be it known that I, WILLIAM R. PENSCHUCK, a citizen of the United States, residing at St. Paul, in the county of Ramsey 5 and State of Minnesota, have invented certain new and useful Improvements in Engines, of which the following is a specification.

The invention comprises a power plant 10 consisting of a water supply, pumps for forcing the water into coils and a supply of compressed air for forcing water from the coils into a steam generator where it is sprayed onto a hot plate thereby forming steam. The steam operates an engine of 15 common type. The exhaust steam from the engine is led into tanks from which it is drawn by pumps operated from the engine and forced into a chamber to be raised to a 20 higher temperature.

A pump operated from the engine forces air through a chamber above the generator where it is heated and through another chamber where it is further heated by a 25 lamp, after which it passes through a coil in the exhaust heating chamber and into said chamber through an escape valve to heat the exhaust steam. The exhaust from this chamber is used to run the air compressor 30 to furnish the compressed air.

To this end the invention consists in the construction, combination, and arrangement of parts hereinafter described and claimed.

In the accompanying drawings forming 35 part of this specification, Figure 1 is a side view of the apparatus; Fig. 2 is a partial section through 2-2 of Fig. 3; Fig. 3 is a top view; Fig. 4 shows valve operating mechanism; Fig. 5 is a section through valve on 40 line 5-5 of Fig. 1; Fig. 6 is a section through valve in opened position; Fig. 7 is a section through valve in closed position; Fig. 8 is a section through exhaust tank on line 8-8 of Fig. 1; Fig. 9 is an enlarged 45 section through generator and hot air tank on line 2-2 of Fig. 3; Fig. 10 is a section through generator and hot air tank on line 10-10 of Fig. 3, and Figs. 11 and 12 are plan and side views, respectively, of a portion 50 of the valve reversing mechanism.

The generator A employs a suitable heater 8 for converting into steam the water intermittently and alternately supplied by pipes B and C to the superposed plate 52 of the 55 casing or boiler 51 (Figs. 10 and 11). These pipes receive the water from a water tank

5 to which they are connected, and as a motor for forcing the liquid through the pipes I employ compressed air from a storage tank 6, the air supply being replenished 60 through the instrumentality of an air compressor 33. A pipe 7 conducts the air from the tank 6 to valves D and E, each of which comprises a fixed casing 53 and a rotatable core 54 provided with a plurality of ports, 65 as depicted in Fig. 5. These valves operate alternately and perform like functions.

The ports 8^a and 9^a connect the pipe 7 with the pipes or coils B and C for forcing the water into the generator A, where 70 it is converted into steam and delivered by conduit 9 for operating the engines 10 and 11. Valve ports 4^a and 5^a control the admission of steam to the engine cylinders, the port 4^a admitting the fluid to the top of the 75 respective cylinder through pipe 68 (66), and the other port, 5^a, admitting the steam through pipe 12^a to the bottom of the cylinder for driving the piston 13 on both strokes. The exhaust port at the opposite 80 end of the cylinder is opened in the respective tank 14 (15) through pipes 69 and 70 and valve ports 6^a and 7^a, from which tanks the exhaust steam is alternately drawn through pipe 73 and port 10^a, by pumps 24 85 and 25, and forced through port 11^a into the exhaust reheating tank 26. Subsequent to being reheated, the exhaust steam is conveyed by pipe 34 for operating the engine 32 of the air compressor 33. From engine 90 32, the exhaust passes through pipe 35 to the water tank 5.

Water is drawn from tank 5 through pipes 18, 19 and 20 and valve port 2^a by the respective one of pumps 16 and 17, and is 95 forced through port 1^a into coils B and C to be further impelled by the compressed air. The air within the coils is released by port 3^a to clear the coils for the next admission or supply of water from the water tank. A 100 passage 23 relieves tank 5 from excessive pressure, which the exhaust steam might otherwise afford. Pump 27 forces air through a heating chamber 28 for preliminary heating and from there the heated air 105 is conducted to chamber 29 where the temperature is further raised by lamp 30. The heated air is then conducted into coils 31, arranged in tank 26, and escapes into the latter for heating the exhaust steam which latter is 110 subsequently utilized for operating the engine 32, as previously set forth. The pistons

13 are connected to the engine shaft 21, the latter serving to drive a shaft 37, to which it is geared as depicted in Figs. 1 and 2, and also operate the valves through the intermediary of a follower lever 40 and link connection 41. Lever 40 is pivoted at 56 and has one end formed with a heel 57 over which the cam 38 rides and its opposite end pivoted to the link 41, as at 58. Thus, it is obvious that 10 rotation of the cam 38 will depress the lever 40 and, through the link and plate connections, effect oscillatory movements of the disks 42 and 43 and consequently, the valve cores.

15 As a means for holding the valves, as positioned by the cam 38, for a predetermined interval, I fix on link 41 an arm 46 which, when elevated, will overlie a stop 47. This stop is pivoted at 49 to a slide member operable by a crank 59, on shaft 21, to which it is connected by link 50. A fixed cam 48 is arranged in the path of the stop 47 to remove the latter from under the arm 46 and thereby permit of the valves returning to normal position for a subsequent operation by cam 38. As the stop 47 is advanced toward the cam 48, it is obvious that the nose of the former will ride to an angular position as shown in Fig. 11. When the slide member 20 is retracted, a spring (not shown) will return the stop 47 to normal position where it will arrest the arm 46 when it is again elevated.

I claim as my invention:

35 1. A power plant of the class described consisting of a source of water supply, a generator, means for generating steam therein, an engine operatively connected with the generator, means operable by the exhaust steam from the engine to compress air for forcing water from said source of supply to the generator, tanks operatively connected with the exhaust port of the engine to re-

ceive the exhaust steam therefrom, means for forcing the exhaust steam from said tanks to 45 a second chamber, an air tank heated by the generator, and means for conducting the heated air to the second chamber for raising the temperature of the exhaust steam to operate said second means. 50

2. A power plant consisting of an engine, a generator, a source of water supply for the generator, coils, means for forcing water from the supply to said coils, and an air compressor operable by the exhaust steam 55 from the engine for supplying air to force the water from said coils into the steam generator.

3. In a power plant of the class described including an engine, a source of water supply, a steam generator, means for forcing water from the supply to said generator, a chamber above the generator, a superheater chamber into which the exhaust steam from the engine is delivered, means for forcing air 60 through the chamber above the generator and through the superheater chamber to be superheated for reheating the exhaust steam. 65

4. In a power plant of the class described including an engine, a source of water supply, a steam generator, a chamber above the generator, a superheater chamber into which the exhaust steam from the engine is delivered, means for forcing air through the chamber above the generator and then 70 through the superheater chamber where it is superheated for heating the exhaust steam, and an air compressor operated by the heated exhaust steam to force water from the supply to the generator. 75

In testimony whereof I affix my signature in presence of two witnesses.

WILLIAM R. PENSCHUCK.
